ESCAPEMENT MECHANISM

Robert Michael Flanagan, Morris Plains, N. J., assignor to Bendix Aviation Corporation, Teterboro, N. J., a corporation of Delaware

Original application January 9, 1945, Serial No. 572,017. Divided and this application December 23, 1946, Serial No. 717,838

2 Claims. (Cl. 171—97)

1

The present application is a division of my copending application Ser. No. 572,017, filed January 9, 1945, and relates to a novel escapement mechanism.

More particularly the present invention relates to a novel snap action escapement mechanism for controlling the operation of a mechanism such as an air distributor valve for inflatable ice eliminating boots or elements.

An object of the invention is to provide a snap action escapement mechanism having a novel compact assemblage.

Another object of the invention is to provide a novel spring wound snap action mechanism, including safety means so arranged that in the event of breakage of the actuating spring a continued driving relation may be effected.

Another object of the invention is to provide a novel snap action mechanism including driving and driven members, together with cam means on the driving member for terminating operation of a driving motor at a predetermined position of the driving member.

These and other objects and features of the invention are pointed out in the following description in terms of the embodiments thereof which are shown in the accompanying drawings. It is to be understood, however, that the drawings are for the purpose of illustration only, and are not designed as a definition of the limits of the invention, reference being had to the appended claims for this purpose.

Figure 1 is an exploded perspective view of the snap action spring actuating mechanism.

Figure 2 is an end view of the mechanism of Figure 1 and showing the same in operating relation.

Figure 3 is a side view of Figure 2.

Figure 4 is an end view of a device embodying the invention and showing a fragmentary sectional view of the snap action mechanism with certain parts broken away to better illustrate the same.

Figure 5 is a diagrammatic view of the energizing circuit for the driving motor of the mechanism and illustrating the operation of the limit switch.

Referring to the drawing of Figure 4, there is provided a main casting or housing 1 which carries a suitable electric motor indicated diagrammatically in Figure 5 by the numeral 2. The motor 2 drives through suitable means described in detail in the copending patent application Ser. No. 572,017 operating mechanism for inflatable ice eliminating elements. The

2

latter operating mechanism includes a pump 3 and a shaft 4 drivingly connected to the motor 2. The shaft 4 is rotatably mounted in suitable bearing members carried by the housing 1. The shaft 4 has a suitable helical or worm gear 5 which in Figure 4 is shown broken away so as to better illustrate the invention.

Operably connected to the worm gear 5 is a gear 6 which is connected to a novel snap action spring actuated escapement mechanism indicated generally by the numeral 7. The latter mechanism effects actuation of a shaft 8 with a snap action so as to adjustably position a rotary valve connected thereto and forming part of a valve mechanism 9. The valve mechanism 9 may be of a type such as shown and described in the copending parent application Ser. No. 572,017 filed January 9, 1945.

The snap action operation of the rotary valve 10 is effected through the operation of the novel escapement mechanism 7 shown in Figure 4 and in detail in Figures 1, 2 and 3.

The escapement mechanism 7 is driven by shaft 4 and gears 5 and 6 from the electric motor 2 as previously described. The gear 6 is freely mounted on the shaft 8 and has affixed thereto a cup shaped member 10 having an end plate 11. The member 10 has formed around the circumferential edge thereof radially projecting escapement cam teeth 12.

As shown in Figure 1, the shaft 8 projects through the cup shaped member 10 and has formed thereon a cam member 13. Radially projecting from the cam member 13 are cam teeth 14 formed around the circumferential edge of the member 13. The cam teeth 14 cooperate with the cam teeth 12 as will be explained hereinafter.

Eccentrically positioned within the cup shaped member 10 and projecting axially from the end plate 11 is a pin 15. This pin 15 is arranged to project through a looped end 16 of a spiral spring 17 positioned within the cup shaped member 10 and about the shaft 8. The opposite end 18 of the spring 17 is fastened by a pin 19 to the cam 13.

A cam slot 20 is formed in the cam 13 and there is disposed in the slot 20 the pin 15. The cam teeth 12 have provided cam surfaces 21 which, as shown in Figures 1 and 2, rise in a counter-clockwise direction from the inner end of the preceding cam tooth 12 to the outer end of the succeeding tooth 12.

The cam teeth 14 have similarly provided cam surfaces 22 which rise in a clockwise direction

from the inner end of the preceding cam tooth 14 to the outer end of the succeeding tooth 14.

The teeth 12 and 14 carried by the members 11 and 13, respectively are positioned circumferentially in spaced relation so that a pawl 23 may be biased under force of a spring 24 so as to fall successively into the interdental spaces between the teeth 12 and 14, as shown in Figure 2. The pawl 23 is slidably mounted in a suitable means provided in the casting 1. The inner end of the pawl 23 rides along the cam surface 21 as the member 10 is rotated in a clockwise direction, as viewed in Figure 1, causing the pawl 23 to move out radially from the shaft 8. Since the pawl locks the tooth 14 from movement, such rotary movement of the driving member 10 winds up or tightens the spring 16 fastened to the members 10 and 13 through the pins 15 and 19 respectively.

The pawl 23 thus moves out radially from the driven shaft 8 and the pin 15 moves in the slot 20 in a clockwise direction until a point is reached where the pawl 23 is raised by the cam surface 21 above the surface of the engaging tooth 14. At the latter point the pawl 23 permits the tooth 14 to move with a snap action in a clockwise direction under tension of the spring 17. The movement of the member 13 under tension of the spring 17 is limited by the pin 15 in the slot 20. Further rotary movement of the cam members 10 then positions the next succeeding tooth 12 so that the pawl 23 is moved under force of the spring 17 into the interdental space between the next succeeding teeth 12 and 14, respectively.

Such snap action movement of the cam member 13 causes a corresponding snap action rotary movement to the driven shaft 8, which in turn imparts a snap action movement to the rotary valve of the mechanism 9, adjusting the same into the next succeeding position, as previously explained.

As shown in Figure 4, the lower end of the driven shaft 8 rotates in a bearing member 24 carried by a plate 25 secured to the casting 1 by bolts 26. The latter end of the shaft 8 rotates upon a positioning screw 27. A removable cap 28 is screw threadedly mounted on the plate 25 and covers the screw 27.

As shown in Figures 3 and 4, there is mounted on the end plate 11 at the outer side thereof a cam surface 29 which at a given position of the driving member 10 actuates a pin 30 operably connected to a lever 31 pivoted at 32 and arranged so as to actuate through a button 33, a switch 34.

The detail structure of the switch 34 is not shown, but the same is preferably of a snap acting normally closed type, well known in the art. Thus upon inward actuation of the button 33 upon a predetermined movement of the pin 30 the switch 34 is opened. The switch 34, as shown in Figure 5, is connected by conductors 35 and 36 in shunt relation to a main control switch 37. The switch 37 is connected in an electrical conductor 38 leading from one terminal of a source of electrical energy 39 to an input terminal of the electric motor 2. Another electrical conductor 40 leads from the opposite terminal of the source of electrical energy 39 to the other input terminal of the motor 2.

The switch 34 is so arranged that if the main control switch 37 be opened, the circuit to the motor 2 will be held closed until the driving member 10 reaches a predetermined position at which the cam 29 opens switch 34. Thus upon

the opening of the main control switch 37, the motor 2 will continue to run until the distributor valve returns to its home position at which switch 34 opens.

It will be readily seen from the foregoing that there has been provided novel compact mechanism in which there is provided a motor 2 which drives an inflating pump 3 and a snap action timing mechanism 7 for operating an air distributor valve mechanism 9 for controlling the inflation and deflation of suitable inflatable elements for removing ice from airfoil surfaces of an aircraft.

Further, there is provided a safety means whereby in the event the actuating spring 17 should break the distributor valve in mechanism 9 will continue to be rotated through the action of pin 15 of the driving member 10 which engages in the slot 20 of the driven member 13 so that there is a direct drive between the motor and the distributor in such emergency.

These and other objects and features of the invention are pointed out in the following description in terms of the embodiment thereof which is shown in the accompanying drawings. It is to be understood, however, that the drawings are for the purpose of illustration only, and are not designed as a definition of the limits of the invention, reference being had to the appended claims for this purpose.

What is claimed is:

1. The combination, comprising, a first element, a second element, spring means drivingly connecting said first and second elements, power means for driving said first element, means for controlling said power means, a releasable holding means normally positioned so as to hold said second element from movement, cam means carried by said first element for urging said holding means in a predetermined direction for releasing said second element under tension of said spring means, engaging means carried by one of said elements for limiting the relative movement between said elements under tension of said spring, actuating means carried by one of said elements, said control means affected by said actuating means for terminating operation of said power means at a predetermined position of said first element, and said engaging means effecting a direct driving connection between said first and second elements upon breakage of the spring means and until termination of operation of said power means by said actuating means.

2. An escapement mechanism comprising, a first rotatable toothed member, a second rotatable toothed member, a shaft, said first member freely mounted on said shaft and said second member affixed to said shaft, one of said members being of a cup shape and the other of said members positioned at the open end of said cup shaped member, a spiral spring positioned within said cup shaped member and about said shaft, said spring drivingly connecting said first and second members, electric motor means for driving one of said members through the other member, the teeth of the first of said toothed members positioned in spaced relation to the teeth of the second of said toothed members, a pawl, means biasing one end of said pawl into the interdental space between a tooth of the first toothed member and a tooth of the second toothed member for holding one of said toothed members from rotation relative to the other of said toothed members, a cam surface carried by said other toothed member for urging said

pawl in a direction for releasing the tooth of said one toothed member for rotation under tension of said spring of said one toothed member relative to said other toothed member, a pin projecting from one of said toothed members, the other of said toothed members having a slot formed therein, and said pin disposed in said slot for limiting the rotary movement of the toothed member under tension of said spring, a circuit for energizing said motor means, switch means for controlling said circuit, and cam means operated by one of said members for opening said switch means and circuit at a predetermined position of said last mentioned member and said pin effecting a direct driving connection between said first and second mem- 10 15

bers upon breakage of the spiral spring and until said cam means opens said switch means.

ROBERT MICHAEL FLANAGAN.
